US00D806901S

(12) **United States Design Patent** (10) **Patent No.:** **US D806,901 S**
(45) **Date of Patent:** **** Jan. 2, 2018**

(54) **TRIM REVEAL EXTRUSION**

(71) Applicant: **EASYTRIM REVEALS INC.**, Calgary (CA)

(72) Inventor: **Joshua George Singh**, Calgary (CA)

(**) Term: **15 Years**

(21) Appl. No.: **29/567,889**

(22) Filed: **Jun. 13, 2016**

Related U.S. Application Data

(62) Division of application No. 13/194,451, filed on Jul. 29, 2011, now Pat. No. 9,366,040.

(57) **CLAIM**

The ornamental design for a trim reveal extrusion, as shown and described.

DESCRIPTION

FIG. 1 is a perspective view of a trim reveal extrusion showing my new design; and,

FIG. 2 is an end elevational view thereof.

The jagged break lines in FIG. 1 represent a cut-line and form no part of the claimed design. the broken lines shown in FIG. 1 represent portions of the trim reveal extrusion that form no part of the claimed design. The broken lines shown in FIG. 2 represent environmental structure which forms no part of the claimed design.

1 Claim, 1 Drawing Sheet
